UNITED STATES PATENT OFFICE.

ANDREW A. BROCK, OF CHICAGO, ILLINOIS.

CARBURETER.

1,011,565.

Specification of Letters Patent. Patented Dec. 12, 1911.

Application filed July 5, 1907. Serial No. 382,177.

To all whom it may concern:

Be it known that I, ANDREW A. BROCK, a citizen of the United States, residing at Chicago, county of Cook, and State of Illinois, have invented certain new and useful Improvements in Carbureters, of which the following is a full, clear, and exact specification.

This invention relates to carbureters for carbureting air with hydro-carbon, or mixing with other combustible fluid the requisite amount of air to support combustion in internal combustion engines, and the invention has more especial reference to that type of carbureters in which the vacuum or partial vacuum created in the carbureter by the draft of the engine, as the engine approaches high speed, is compensated for automatically by an auxiliary supply of air and the mixture thereby prevented from becoming too rich.

One of the important objects of the invention is to provide an improved and simple form of carbureter in which the combustible fluid will be supplied to the air in an enveloping stream or column, so that the column of air entering the carbureter will be substantially inclosed by the combustible fluid.

A further object of the invention is to provide an improved and simple form of carbureter in which the auxiliary air will be supplied to the center of the column of air, and a still further object is to provide improved and simple means whereby the auxiliary air inlet will be automatically governed positively in unison with the movement of the throttle. And the invention has for its object finally to provide an improved and simple form of carbureter in which the fuel supply will be governed positively and automatically in accord with the position of the throttle.

With a view to the attainment of these ends and the accomplishment of certain objects of minor importance hereinafter appearing, the invention consists in the features of novelty which now will be described with reference to the accompanying drawings and then more fully pointed out in the claims.

In the said drawings—Figure 1 is a vertical sectional view of a carbureter embodying this invention. Fig. 2 is a side elevation thereof. Fig. 3 is a plan view of the controlling handle or lever and its associated parts. Fig. 4 is a vertical section on the

line 4—4 of Fig. 3. Fig. 5 is an enlarged transverse section of the fuel regulating and spraying nozzle. Fig. 6 is a vertical section therecf, on line 6—6 of Fig. 5. Fig. 7 is an enlarged detail plan view of the upper end of the auxiliary air tube. Fig. 8 is a side elevation thereof. Fig. 9 is an enlarged detail section taken on line 9—9 of Fig. 1. Fig. 10 is an enlarged detail section of the means for adjusting the elevation of the float lever pivot hereinafter described, and Fig. 11 is a detail end view of such pivot.

1 is a float chamber which may be provided as usual with any suitable inlet connection 2 having a regulating valve 3, which in this example of the invention is held to its seat by a coil spring 4 resting upon a shoulder 5 on the valve stem 6, whose upper end is guided by a cap 7 against which the upper end of the spring bears. Within the chamber 1 is situated an appropriate float 8 which, when the chamber is empty, rests upon the branches of a forked lever 9 supported upon a pivot 10 and having its shorter end engaging under the shoulder 11 for lifting the valve 3 more or less as the supply in the chamber 1 decreases. In order that the level of the liquid in the chamber 1 may be regulated or governed to suit the exigencies of the carbureter, the elevation of the pivot 10 with relation to the shoulder 5 may be altered, and to that end the pivot 10, as better shown in Figs. 10 and 11, is mounted eccentrically upon the inner plain end 12 of a screw 13 which is screw threaded in a socket boss 14 on the side of the float chamber, so that by turning the screw the pivot 10 may be raised or lowered. Between the inner end of the screw and the bottom of the socket in which it is situated may be arranged a gasket or packing 15, composed of some suitable yielding material which will keep the joint tight and at the same time permit the screw to be rotated sufficiently to adjust the pivot 10.

In the bottom of the float chamber 1 is formed an air inlet port or passage 16 which is surrounded by and communicates with a stand-pipe 17 provided at its upper end with a beveled edge 18, or is otherwise suitably formed to constitute a valve seat for coöperation with an annular valve 19 formed within a sleeve 20, which is telescoped with the upper end of the stand-pipe 17. As better shown in Figs. 5 and 6, the periphery of the pipe 17 at its upper end

is provided with a suitable number of channels 21 extending upwardly through the face of the valve seat 18, and the sleeve 20 below the valve 19 is formed with a shoulder 22 which fits the periphery of the pipe 17 with reasonable snugness and is of sufficient length or vertical extent to substantially cover the passages 21 when the valve 19 comes to rest upon its seat 18, the sleeve 20 being considerably larger than the pipe 17 at its lower end below the shoulder 22, so that when the valve 19 is seated the passages or channels 21 will be completely closed and communication between the interior of the sleeve 20 and the float chamber 1 will be intercepted. When the valve 19 is more or less elevated with respect to its seat 18, this communication will be more or less opened and the gasoline or other fluid in the float chamber 1 will be entrained into the sleeve 20 by the current of air passing upwardly through the stand-pipe 17, and the valve seat 18, which is also of an annular form, and it will be observed that the column of air thus entering the apparatus will be enveloped by an annular column or stream of combustible fluid issuing from between the valve seat 18 and valve 19 whose surfaces constitute continuous lips for creating a complete ring of the combustible around the air. In order that the quantity of combustible fluid thus admitted to the air may be regulated as required, the sleeve 20 is provided with exterior adjusting means consisting preferably of a thumb nut 23 screw threaded on the upper end of a threaded stem 24, which is secured by a spider 25 within the sleeve 20 and passes loosely through the top of the outlet neck 26, so that by rotating the thumb nut 23 the valve may be more or less opened. The valve may be lowered when the thumb nut 23 is unscrewed by a spring 27 or other suitable means sleeved upon the stem 24, and bearing between a shoulder 28 on the stem and the upper side of the outlet neck 26. When the valve 19 is in its normal or working position, the lower end of the sleeve 20 dips sufficiently into the liquid of the chamber 1 to cause the liquid to be elevated, even though its level be considerably below normal. The upward movement of the sleeve 20 may be limited by a shoulder 29 formed thereon in position to go into engagement with a depending portion 30 of the outlet neck 26 which is telescoped with the sleeve 20 and forms a substantially air-tight connection between the sleeve and said outlet neck, but it is, of course, desirable, nevertheless, that the lower end of the extension 30 be above the normal level of the liquid in the float chamber 1, so as to avoid any possibility of the liquid being entrained into the neck 26 of the carburetor through this joint. The outlet neck 26 and the down-

ward extension 30 thereof are formed upon a cap or cover 31 secured to the float chamber 1 by screws 32 or other suitable means whereby the float may be removed when this cap or cover is detached, and it is apparent that in assembling the elements the neck 20 and its connected parts will be carried by the cap 31 and introduced over the stand-pipe 17 after the float 20, which is of annular form, has been placed in the chamber 1 around said stand-pipe. 70 75

The amount of air passing the valve seat 18 may be regulated as desired by a throttle 33 supported within the stand-pipe 17 by means of a downward extension 34 on the lower end of stem 24, so that the throttle will be adjusted in unison with the fuel valve 19, these two valves being so fixed with relation to their respective seats as to maintain the proper proportion of air and fuel. The seat for the throttle 33 is formed by an internal or annular enlargement 35 within the pipe 17 at its upper end, although it is, of course, understood that in practice it may never be necessary to bring the throttle 33 into actual contact with its seat. The portion carrying the throttle 33 is preferably in the form of a tube 36 so that it may be utilized as a passage for the auxiliary air to the interior of the column of air and fuel. 90 95

The valve 33 as shown in Fig. 1 is flared outwardly so that as the air rising through the stand-pipe 17 strikes it, it will be deflected outwardly across the annular opening between the valve 19 and its seat 18, and thereby be converted into a thin annular sheet or column highly rarefied and of great velocity by reason of this reduction in the size of the passage. This serves to entrain the gasoline or other fuel from the chamber 1, causing it to rise in the space between the stand-pipe 17 and sleeve 20 and through the channels 21, whence it impinges the outwardly inclining annular valve 19 and is converted into an annular column surrounding the annular column of air emerging from the space between the throttle 33 and seat 35. The auxiliary air which is admitted through the tube 36 into the center of this annular column of air and fuel is broken up into a number of streams by means of a spider or plurality of spokes 37 radiating from the extension 34 to the walls of the tube 36, and the column of air and fuel surrounding the tube 36 is partially admitted between these streams of auxiliary air by side passages 38 formed in the upper end of the tube 36 at points between some of the spokes 37 as shown in Figs. 7 and 8, thus causing a more intimate association of the auxiliary air with the mixture. As the column rises above the tube 36, it encounters the spider 25 and is thereby further broken up and a more thorough commingling of the air and fuel created. The lower end of the auxil- 105 110 115 120 125 130

5 auxiliary air tube 36 is inserted in a cup 39 and is provided in its side with an inlet port 40, and one side of the cup 39 is provided with a valve 41 which is of semi-cylindrical form fitting partially around the tube 36, so that when the tube is in a certain position, the inlet port 40 will be closed or may be more or less open, according to the position of the regulating lever or handle of the carbureter.

10 During the operation of the carbureter the valve 41 is stationary, while the tube 36 moves, but the position of the valve 41 may, if desired, be altered with relation to the 15 position of the port 40 by rotating the valve 41 upon its vertical axis. To that end the cup 39 is secured to a set screw 42 which is preferably journaled in the lower side of mouth-piece 43 and provided with a set nut 44 capable of clamping the cup in position, the set screw being also provided with a turning handle 45 whereby the valve 41 may be positioned when the nut 44 is released. It will thus be seen that when it is 20 not desired to have any auxiliary air, the lower end of the auxiliary air tube 36 will be completely closed by the cup 39 and the port 40 will be closed by the valve 41, but should the degree of vacuum in the outlet 25 neck 26 of the carbureter require additional air over and above that which may be admitted around the throttle 33, the result may be accomplished by rotary movement of the tube 36, and this being secured permanently 30 to the valve stem 24, it of course follows that the auxiliary air will be admitted automatically when said valve stem is rotated to admit a larger proportion of fuel. This 35 opening and closing action of the fuel valve 19 and throttle 33 resulting from the rotation of the stem 24 may be caused by any suitable device having proper operative relation to said stem and preferably by means 40 of a cam 46 threaded upon the upper end of the stem 24 and formed on or secured to the 45 operating handle 46^a and engaging a corresponding cam face 47 formed on the top of the outlet neck 26, so that when the lever or handle 46^a is oscillated in one direction, 50 the coöperating cam faces 46, 47 will lift the stem 24 by engagement with the adjusting nut 23 and when moved in the other direction will permit the stem to be lowered by the spring 27.

55 48 is a throttle pivoted on the shaft 49 in horizontal extension 50 to the outlet neck, and in order that the rising and falling movement of the fuel valve 19 and air throttle 33 may result in a corresponding adjustment of the throttle 48, the shaft 49 is provided with a pinion 51 engaging with a segment 52 on the edge of the cam 46. The outlet neck of the carbureter of course leads to the engine or other device which is to be supplied with the combustible mixture, and in

order that the same may be adapted for either vertical or horizontal connection, the horizontal extension 50 of the outlet neck terminates in a plane at substantially 135° to the vertical plane, and to this is secured a 70 removable section 53, which, when placed upon the extension 50 in the position shown in Fig. 1, constitutes a right-angle elbow, but when given a half-turn to the position shown in dotted lines, constitutes a horizontal continuation of the extension 50. 75

In order that the invention may be understood by those skilled in the art, the details of an exemplification thereof have been thus specifically described, but

80 What I claim as new and desire to secure by Letters Patent is:—

1. In a carbureter the combination of a throttle, means for operating the throttle, means for creating an annular column of air, means for regulating said column of air in unison with the movement of the throttle, means for creating a hollow stream of fluid fuel enveloping said column of air, means for regulating the fuel in unison with the movement of the throttle and means operatively connected with the throttle for admitting auxiliary air. 85

90 2. In a carbureter the combination of a chamber for fluid fuel, an annular valve seat, an annular valve arranged to coöperate with said seat, said seat and valve being so disposed with relation to said chamber as to admit the fluid from the chamber between them to control the supply of fluid, 95 and means for directing a current of air through said annular valve seat. 100

105 3. In a carbureter the combination of a fuel chamber, a stand-pipe therein communicating with the atmosphere and provided at its inner end with an annular valve seat, a sleeve telescoped with said stand-pipe and having an annular valve coöperating with said seat, and means for adjusting said sleeve and thereby regulating the opening 110 between said valve and seat.

115 4. In a carbureter the combination of a fuel chamber, a stand-pipe rising therein and communicating with the atmosphere and having an annular valve seat at its inner end, a sleeve telescoped with said stand-pipe and having an annular valve coöperating with said valve seat, an outlet passage for the carbureter with which said sleeve has telescopic communication, and means for adjusting said sleeve with relation to said pipe. 120

125 5. In a carbureter the combination of a fuel chamber, a stand-pipe rising therein and having communication with the atmosphere and provided at its inner end with an annular valve seat, a sleeve telescoped with said stand-pipe and having an annular valve coöperating with said seat, means for adjusting said sleeve with relation to said pipe, a throttle situated within said annular valve 130

- seat for controlling the passage of air through said valve seat, and means for adjusting said throttle.
6. In a carbureter the combination of a fuel chamber, a stand-pipe rising therein and communicating with the atmosphere and provided at its inner end with an annular valve seat, a sleeve telescoped with said pipe and having an annular valve co-operating with said seat, a throttle within said annular seat for regulating the passage of air therethrough, and means for adjusting said valve and throttle simultaneously.
7. In a carbureter the combination of a fuel chamber, a stand-pipe therein communicating with the atmosphere and having an annular valve seat at its inner end, a sleeve telescoped with said pipe and having an annular valve co-operating with said seat, an auxiliary air inlet tube arranged within said pipe, a throttle on the inner end of said tube situated within said annular valve seat for controlling the passage of air through said pipe, a port in the side of the tube for admitting air thereto, means arranged to cover said port and means whereby said tube may be moved longitudinally to vary the amount of air passing through said pipe and move rotatively to vary the amount of air admitted through said port.
8. In a carbureter the combination of a fuel chamber, a stand-pipe therein communicating with the atmosphere, and having an annular valve seat at its inner end, a sleeve telescoped with said pipe and having an annular valve co-operating with said seat, an auxiliary air tube arranged within said pipe and having a throttle situated within said annular valve seat, means for admitting air to said tube when the tube is rotated and means for simultaneously rotating and reciprocating said tube and also reciprocating said sleeve.
9. In a carbureter the combination of a fuel chamber, a stand-pipe therein communicating with the atmosphere and having an annular valve seat at its inner end, a throttle situated within said pipe for controlling the amount of air passing therethrough, an auxiliary air inlet tube con-
- nected with said throttle and having an air inlet port in its side, a cup receiving the lower end of said tube, a valve on said cup partially surrounding said tube for regulating said port, means for rotatively adjusting said cup and last said valve, a sleeve telescoped with said pipe and having an annular valve co-operating with said seat, and means for rotating and reciprocating said tube.
10. In a carbureter the combination of an annular fuel regulating valve, an annular valve seat therefor having communication with the external atmosphere, an auxiliary air inlet tube having communication with the atmosphere at its outer end and provided at its inner end with a throttle for regulating the air passing through said annular valve seat, a valve for controlling the auxiliary air entering said tube, conforming to the cylindrical exterior of the tube and rotatable on the axis of the tube, means for thus rotating the last said valve and locking it in position with relation to the tube, and means for rotating the tube to regulate the amount of auxiliary air admitted thereto.
11. In a carbureter, the combination of a fuel chamber, a stand pipe communicating therewith and provided with an annular valve seat, an annular valve co-operating with the seat, means for supplying a fluid fuel between the valve and its seat to form a complete annular stream of fuel within the stand pipe and against the wall thereof, means for creating a column of air within the annular column of fuel and for directing the air against the wall of the stand pipe to remove the fuel therefrom and combine therewith, and means for adjusting the valve with relation to its seat to vary the supply of fuel.
- In testimony whereof I have signed my name to this specification, in the presence of two subscribing witnesses, on this 1st day of July A. D. 1907.
